H. A. Harvey

United States Patent Office.

HAYWARD A. HARVEY, OF ORANGE, NEW JERSEY.

Letters Patent No. 66,331, dated July 2, 1867.

IMPROVEMENT IN NAILS.

The Schedule referred to in these Letters Patent and making part of the same.

TO ALL WHOM IT MAY CONCERN:

Be it known that I, HAYWARD A. HARVEY, of Orange, in the county of Essex, and State of New Jersey, have invented certain new and useful Improvements in Nails: and I do hereby declare that the following is a full, clear, and exact description thereof.

The nature of my invention consists in making a nail either of square or round wire, with the head either finished or unfinished, having upon its shank compressions forming cavities at intervals on two sides and projections upon the edges, with the object of presenting inequalities of surface in two directions so as to meet the greatest elasticity of the wood into which the nail may be driven, whether it be driven parallel to or across the grain of the wood. The drawings which accompany and form a part of this specification comprise two views of the nail—

Figures 1 and 2 showing the compressions both on the face and upon the edge, together with another drawing.

Figure 3 showing a modified form of my invention which will be hereinafter described.

Similar letters of reference indicate the same parts in all the figures.

a represents the head, *b* the shank, *c c c* the cavities, *d* the protuberances, and *e* the point of the nail.

I am aware various efforts have been made both with nails and staples to accomplish the purpose for which my invention is designed, but I have never seen or known of a nail having the peculiarity of cavities and protuberances in two directions, as herein described. A patent was granted to me on the 2d of April, 1867, for a staple, the legs of which had this peculiarity. I now propose to combine these inequalities of surface with a head, thus forming a nail which will have the increased holding qualities that I secure for my staple.

Fig. 3 represents a round head nail, but having a portion of the metal forming the protuberances *d d d d d d* cut away so as to present a series of ratchets, and therefore still greater and more abrupt resistance to the withdrawal of the nail after the wood into which it has been driven has by its natural elasticity conformed itself to the inequality of surface upon the edges.

I do not confine myself to any particular form or shape of head nor of point, nor to a finished or shaved head, although I think that by shaving the head the finished appearance of the nail will make it especially desirable for use in those cases where screws are now used and are not intended to be withdrawn. I would also remark that for some purposes I conceive that a flat or chisel point will be preferable to the diamond point.

What I claim as my invention, and desire to secure by Letters Patent of the United States, is—

The combination of the head of a nail with one or more cavities and protuberances or ratchets upon the sides and edges of the shank thereof, substantially as described, whereby the lateral diameter or width of the shank is increased, as shown.
